UNITED STATES PATENT OFFICE

2,184,676

HATCH COVER

James F. Mackin, Chicago, Ill.

Application November 18, 1937, Serial No. 175,185

9 Claims. (Cl. 114—202)

This invention relates to hatch covers for vessels and for use in closing floor openings in situations similar to those of the hatches in the deck of a vessel, as for example, in warehouse floors. One object of the invention is to provide a unitary cover and means for removing it readily by mechanical power. Another object is to provide means adapted to operate in conjunction with similar means on other hatch covers so that an entire series of covers may be removed at one time. Another object is to provide for replacement of the covers by mechanical means. The invention therefore consists in the combination of elements and features herein described and shown in the drawing, as indicated by the claims.

In the drawing:

Figure 1 is a side elevation of a hatch cover embodying this invention.

Figure 2 is a front elevation of the same.

Figure 3 is an enlarged detail view showing in side elevation, and partly in section, the lifting means for releasing the hatch cover from its coaming.

Figure 4 is a detail section taken as indicated at line 4—4 on Figure 3.

Figure 5 is a detail elevation similar to Figure 3, showing a modified construction.

Figure 6 is a detail section taken as indicated at line 6—6 on Figure 5.

In the drawing, the coaming is shown at 1, formed with the usual base flange 2, by which it is secured to the floor or decking, and having a second flange 3, to support the cover. The cover is shown at 4, also provided with a flange 5, adapted to mate with the flange 3 and, as indicated in Figure 3, the cover telescopes over the upper edge portion 6 of the coaming which rises above its flange 3. If desired, a layer of packing material 7 may be interposed between the flanges 3 and 5 when the cover is in closed position. In that position the cover may be secured by any suitable fastenings, such as the eccentric clamping devices 8, each of which is attached to the under side of the coaming flange 3 by a pivotal connection 9, so that when the eccentric 10 is rotated to releasing position, the entire clamp can be swung downwardly about its pivot 9 and will hang substantially within the outline of the base flange 2 of the coaming.

Extending adjacent the coaming at two sides are parallel T-rails 11, forming a track upon which the cover may travel when it is removed from the coaming. To facilitate such removal I provide the cover with two pairs of wheels, preferably of the flanged type, adapted to travel on the

rails 11. The wheels 12 of one pair are carried by bracket arms 13, secured to opposite sides of the cover just above its flange 5 and extending forwardly,—that is, in the direction in which the cover will travel for removal from the coaming 1. 5 Each of the wheels 14 of the other pair is connected to the cover 4 by adjustable means arranged for raising the cover with respect to the wheels 14, high enough so that its "rear" edge will clear the upstanding rim 6 of the coaming, as 10 shown in Figure 3. In the form illustrated in Figures 1 to 4, this adjustable means includes a post 15, pivotally attached to the cover at 16 and slidably guided between triangular frame plates 17, which rise from the axle 18 of the wheel 14. 15 The post 15 is formed on one face with gear teeth 19 and on the opposite face with ratchet teeth 20. A segmental gear 21 is carried on a shaft 22 between the frame plates 17, and said shaft is provided with a lever arm 23 upstanding in a vertical 20 plane so that rocking of the arm 23 about the axis of shaft 22 operates the gear 21, for raising or lowering the post 15 in the guideway formed by the plates 17 and thus serves for raising or lowering the cover 4 with respect to the "rear" edge of 25 the coaming 6. When the cover is thus elevated, it may be retained at such position by a ratchet pawl 24 pivoted on a stud 25 and carried between the frame plates 17. The assembly comprising the plates 17 and the adjustable post 15 is connected to the hatch cover 4 only by means of a single pivot 16 and is pivotally supported on the axle 18 of the wheel 14; therefore, to stabilize this support a tie rod 26 extends from the axle 18 to the axle of the corresponding wheel 12 at the 30 35 "forward" edge of the hatch cover, as seen in Figure 1.

As indicated in Figure 2, both wheels 14, at the "rear" end of the cover 4, are provided with adjustable supports like that shown in Figure 3. 40 The levers 23 may be operated in any convenient manner for elevating the rear edge of the cover so that it may be rolled forward clear of the coaming, and then left standing on the rails 11 until the hatch is to be closed again. If desired, a cable 27 45 may extend to a suitable winch, and if there are several hatches arranged in a row on the deck, the same cable may be attached to the operating levers 23 of all the covers, so that by operation of the winch all the covers may be raised simultaneously and drawn forward to open the hatches. The same cable, or a separate one, may extend in the opposite direction, as indicated at 28, for operation by a second winch to draw the cover or group of covers 4 back into position over the 50 55

hatches. Since only one edge of each cover is elevated, the other edge will engage the upstanding rim portion 6 of the coaming, and the cover will be thus arrested in properly registered position. A reverse pull on the operating cables will relieve the pressure on the ratchet pawls 24 and these may then be flipped out of engagement with the ratchet teeth, permitting the covers to be lowered under control of the winch. Each pawl 10 includes a finger-piece 29 for this purpose.

When the covers have been replaced with their flanges 5 resting on the flanges 3 of the coamings, each cover may be secured by swinging the fasteners 8 up over the flanges 5 and clamping them in locking position, as seen in Figure 2. To stiffen the flanges 3 of the coaming, I may provide vertical bracing flanges, as shown, between the flanges 3 and the base flange 2, thus insuring a watertight engagement with the cover flanges 5.

Figure 5 illustrates a modified structure for elevating the hatch cover. In this case the operating lever 30 is integral with an arm 31, which is mounted at its lower end on the axle 32 of the wheel 14. Thus, when this lever is swung about its fulcrum pivot 33, which is fixed to the hatch cover 4^a, the arm 31 is shifted from the inclined position shown in full lines in Figure 5, to the vertical position shown in dotted outline, thus elevating the fulcrum 33 and carrying the edge of the hatch cover 4^a upwardly, clear of the coaming. The arm 31 may carry a ratchet pawl 34, engageable with ratchet teeth 35, fixed to the flange 5^a of the hatch cover. A stop shoulder 36 may be associated with the ratchet teeth 35 to limit the swing of the lever at its vertical position, so that when the lever arrives at its limit, further tension in the cable 27 will operate to cause travel of the cover along the rails 11.

It may be noted that in both forms of the invention herein illustrated, the fixed wheels 12 being carried on brackets 13 which extend beyond the rim flanges 5 of the hatch cover, may be adjusted to stand normally just off the running rails 11 when the cover is in closed position. This will insure that the wheels will not interfere with clamping the cover firmly onto the supporting flange 3 of the coaming 1. Then, upon the tilting of the cover, as its opposite edge is raised by the adjustable supports on the wheels 14, the wheels 12 will be slightly lowered as the cover rocks about the edge of the flange 3, adjacent the wheels 12, and will come into contact with the rails immediately, or, in any event, shortly after the cover starts its shifting movement. Preferably, the wheels 12 should be mounted so as to contact with the rails 11 immediately upon the tilting of the cover, so that it may be easily rolled off the coaming. To insure this relation of the wheels 12 to the track, they are shown carried on threaded posts which are thus rendered vertically adjustable in the brackets 13 and which may be secured at any position of adjustment by clamping nuts 13^a.

While there is shown and described herein certain specific structure embodying the invention, it will be manifest to those skilled in the art that various modifications and rearrangements of the parts may be made without departing from the spirit and scope of the invention, and that the same is not limited to the particular form herein shown and described, except in so far as indicated by the appended claims.

I claim:

1. In combination, a coaming having an upstanding rim flange, a unitary hatch cover formed

to telescope with said flange and outside thereof, parallel rails extending respectively adjacent opposite sides of the coaming, two pairs of wheels positioned to rest on said rails, one pair adjacent one edge of the cover and the other pair adjacent its opposite edge, means connecting the one pair to the cover in fixed relation thereto, vertically extensible means connecting the other pair to the cover, and means for adjusting such connection sufficiently to raise the adjacent edge clear of the upstanding flange of the coaming so that the cover may be removed bodily by travel along the rails.

2. In combination, a coaming having an upstanding rim flange, a unitary hatch cover formed to telescope with said flange and outside thereof, parallel rails extending respectively adjacent opposite sides of the coaming, two pairs of wheels positioned to rest on said rails, one pair adjacent one edge of the cover and the other pair adjacent its opposite edge, bracket means connecting the one pair to the cover in fixed relation thereto with their axis slightly beyond its edge, vertically extensible means connecting the other pair to the cover, and means for adjusting such connection sufficiently to raise the adjacent edge clear of the upstanding flange of the coaming so that the cover may be removed bodily by travel along the rails.

3. In combination, a coaming having an upstanding rim flange, a unitary hatch cover formed to telescope with said flange outside thereof, parallel rails extending respectively adjacent opposite sides of the coaming, two pairs of wheels positioned to rest on said rails, one pair adjacent one edge of the cover and the other pair adjacent its opposite edge, means connecting the one pair to the cover in fixed relation thereto, vertically extensible means connecting the other pair to the cover, and means for adjusting such connection sufficiently to raise the adjacent edge clear of the upstanding flange of the coaming so that the cover may be removed bodily by travel along the rails, together with horizontally movable actuating means for said adjusting means including a cable extending past the fixed wheels in the direction in which the cover travels for removal, whereby tension on said cable serves to raise the edge adjacent the said other wheels and a continued pull on the cable moves the cover along the rails.

4. In combination, a coaming having an upstanding rim flange, a unitary hatch cover formed to telescope with said flange and outside thereof, parallel rails extending respectively adjacent opposite sides of the coaming, a pair of wheels secured to the cover adjacent one edge thereof and in fixed relation thereto, positioned to rest on said rails, and a second pair of wheels positioned to rest on the rails adjacent the opposite edge of the cover, vertically extensible means connecting said second pair to the cover and means for adjusting such connection adjustable sufficiently to elevate the adjacent edge clear of the upstanding flange of the coaming so that the cover may be removed bodily by travel along the rails, horizontally movable actuating means for said adjusting means including a cable extending past the fixed wheels in the direction in which the cover travels for removal, whereby tension on said cable serves to raise the edge adjacent the said other wheels, and a continued pull on said cable moves the cover along the rails; together with automatic detent means opposing retraction of said vertically adjustable connection and

thus serving to hold said edge of the cover elevated when the tension on said cable is relaxed.

which the cover travels for removal, whereby tension on said cable serves to rock the lever and adjust the connecting means to raise the edge of the cover adjacent said other wheels, and a continued pull on the cable moves the cover along the rails, and a second cable attached to said lever extending in the opposite direction from the first cable for returning the lever to its position over the coaming, together with automatic detent means operating independently of said lever to retain the adjustable connection in position for holding the cover elevated when the tension of the first cable is relaxed and to prevent the tension of the second cable from lowering the cover.

8. In combination, a coaming having an up-standing rim flange, a unitary hatch cover formed to telescope with said flange and outside thereof, parallel rails extending respectively adjacent opposite sides of the coaming, two pairs of wheels positioned to rest on said rails, one pair adjacent one edge of the cover and the other pair adjacent its opposite edge, means connecting the one pair to the cover in fixed relation thereto, vertically extensible means connecting the other pair to the cover, and means for adjusting such connection sufficiently to raise the adjacent edge clear of the upstanding flange of the coaming so that the cover may be removed bodily by travel along the rails, and actuating means for said adjusting means including an upstanding lever and a cable attached thereto extending horizontally past the fixed wheels in the direction in which the cover travels for removal, whereby tension on said cable serves to raise the edge adjacent said other wheels, and a continued pull on the cable moves the cover along the rails; and automatic detent means operating independently of said lever to retain the adjustable connection in cover-elevating position, whereby a second cable may be attached to said cover extending in the direction in which the cover travels for replacement and may be employed for returning the cover to its position over the coaming.

9. In combination with a plurality of hatches 45
each comprising a coaming having an upstanding rim flange and a unitary hatch cover formed to telescope with said flange and outside thereof, a pair of rails extending respectively adjacent opposite sides of each coaming, wheels on each cover positioned to rest on said rails and comprising one pair of wheels adjacent one edge of the cover and another pair of wheels adjacent its opposite edge, means connecting the one pair to the cover in fixed relation thereto, vertically extensible means connecting the other pair to the cover, and means for adjusting such connection sufficiently to raise the adjacent edge clear of the upstanding flange of the coaming so that the cover may be removed bodily by travel along the rails, the elevated edge of the cover being shifted across the hatch opening by such travel; and common actuating means for operating said adjusting means of all the covers simultaneously including a cable extending horizontally past the fixed wheels of all the covers in the direction in which they travel for removal, whereby tension on said cable serves to raise the edge of each cover adjacent its said other wheels, and a continued pull on the cable moves the covers along the rails and clear of their respective hatches. 60 65 70

JAMES F. MACKIN.
